DESIGN FOR A FOLLOWER BLOCK FOR A FILING DRAWER

David B. Hull, Bethesda, Md.

Application July 3, 1942, Serial No. 107,402

Term of patent 7 years

To all whom it may concern:

Be it known that I, David B. Hull, a citizen of the United States, residing at Bethesda, in the county of Montgomery, and State of Maryland, have invented a new, original, and ornamental Design for a Follower Block for a Filing Drawer, of which the following is a specification, reference being had to the accompanying drawing, forming a part thereof.

In the drawing:

Figure 1 is a perspective view of the follower block for a filing drawer, showing my design; and

Figure 2 is a vertical cross-sectional view thereof.

The dominant feature of my design resides in the portion shown in full lines in the drawing.

I claim:

The ornamental design for a follower block for a filing drawer, as shown and described.

DAVID B. HULL.
